WINDOW LOCK FASTENER

Samuel Segal, New York, N. Y.

Application May 5, 1931. Serial No. 535,141

3 Claims. (Cl. 292—251)

The present invention has general reference to a fastener for maintaining companion window frame members against movement and rattling within the rails or guiding channels of a casing normally containing said members in slideable relation and more particularly the invention aims to provide a construction and arrangement whereby the frame members may be suitably locked with reference to one another in any position namely, either, closed, or open or partly open, although in a broader aspect, the invention comprehends a fastener which may be applied to a wall of a casing supporting one or more window frames for securing either of these against movement or rattling.

A feature of the invention is to provide an improved fastener having a novel clamping element mounted on a supporting member containing a clutch which is responsive to the actuation of said element, if the latter be rotated in one direction concomitantly providing a guard against retraction of the element upon the rotation thereof in an opposite direction.

Another feature of the invention is to provide a manually controlled clutch which if rendered inoperative permits either the clamping member to be adjusted forwardly or rearwardly with respect to its support or withdrawn therefrom.

Another aspect of the invention contemplates the provision of a clamping device which releases the clutch on each revolution to permit the device to operate or alternatively is prevented from being operated by the action of the clutch.

Still another feature of the invention is to provide a novel fastener easy to operate and quick to adjust, economical to manufacture and comprises relatively few parts.

The invention will be better understood from the following detailed description of one exemplification, reference being had to the annexed sheet of drawing in which:

Fig. 1 is a plan view of the fastener or window lock shown partly in section, mounted on a window frame casing and secured against a window frame.

Fig. 2 is a view taken along the line 2—2 of Fig. 1 in the direction of the arrows.

Fig. 3 is a section taken along the line 3—3 of Fig. 2 in the direction of the arrows showing the clutch in the normal or raised position.

Fig. 4 is a fragmentary sectional view illustrating the clutch depressed to permit retraction of the clamping element.

Fig. 5 is a perspective view of the window lock fastener shown mounted on the lower forwardly

disposed window frame and tightened against the upper rear window frame or sash.

With the embodiment of my invention illustrated in the accompanying drawing, it is desired to lock and fasten the front and rear window frame or sash members 10 and 11 respectively in any relative position with respect to one another against the walls of casing 9 and in this connection the fastener broadly designated 12 comprises a clamp and clutch supporting body or boss 13, cast to the design shown and includes the integrally associated flat bottom base plate 14 which terminates laterally thereof in ears or wings 15, each of which is bored and countersunk to permit entrance of a securing member 16 for rigidly holding the fastener 12 to a transverse brace as 17 of the front window frame member 11 (Fig. 5) or to one wall of the frame casing 9 (Fig. 1).

The clamp and clutch support 12 is provided with the threaded bore 18 longitudinally disposed and coextensive the length thereof and embodies a laterally disposed offset 19 having a recess 20 which intersects and communicates with aforementioned bore 18, the latter being reentrant, that is, extends downwardly and inwardly into the body of the clamp and clutch support 12 and terminates within proximity of the bottom plane of the base plate 14, defining generally a pocket in which the clutch broadly denoted 21 is yieldingly sustained by the spring 22 interposed between one end thereof and the bottom wall of recess 20.

Clutch 21 is in the form of a one piece stud comprising an elongated body having the head portion 23, an intermediate restricted connecting member 24, a shoulder or step defining an enlarged portion 25 and a flange 26 yieldingly supported by spring 22.

Operatively connected with the longitudinally disposed threaded bore 18 is the clamping element generally designated 27 which embodies an elongated threaded stem or bolt 28 suitably carrying at one end thereof the socket or housing 29 in which preferably a resilient member of rubber or a squeegee 30 is secured, it being understood, that instead of securing a yieldable or soft material in the housing, both the housing and squeegee may be eliminated and the stem 28 may be tightened directly against a brace of the upper sash or if the housing with the squeegee be employed, the latter may be also tightened against the upper sash as in Fig. 5 or against a brace of sash 11, the latter being representative of either a front or rear slideable sash, if

the fastener is mounted on the frame or sash casing as in (Fig. 1). At the other end of the clamping element, the stem is formed with an eye 29' providing means for moving the 5 squeegee either towards or away from the adjacent frame member as is well understood.

It should be observed that the stem, although threaded comprises a longitudinally disposed flat face 31' which cooperates with the flange 10 or disc 26 of the clutch to prevent retraction of the stem, if the clutch 21 is in its normal or raised position (Figs. 1, 3, and 5). In other words, flange 26 of the clutch, normally by reason of the action of spring 22 is in a position 15 slightly overhanging bore 18 (see Fig. 3) and provides an abutment or stop for the marginal portion 32 of the flat face of the stem, if the latter is moved, say, counter clockwise looking in the direction from manipulator 29' towards 20 the squeegee or clockwise looking in the direction from the squeegee to manipulator thereby preventing any further movement of the stem in the same direction.

If, however, it is desired to move the 25 squeegee to a clamping position, the stem is manipulated by manually actuating the eye 29' in a clockwise direction, looking in the direction of manipulator or eye 29' towards the squeegee thus causing the marginal portion 31 of the flat 30 face 31' to abut and drive against shoulder 25 and drive flange 26 against the spring 22 and consequently move the stud bodily inwardly against the action of spring 22 until the intermediate restricted portion 24 of the stud is in 35 spatial registry with the stem, whereby the latter may be turned freely in completing its revolution by virtue of the clearance between the restricted portion of the stud and said stem (see Fig. 4).

40 On each revolution of the stem during the progression of the squeegee towards the adjacent sash to be secured, the driving margin 31 of the flat face contacts against the shoulder 25 and drives the stud bodily against the spring, causing 45 the stem to be operatively free of the clutch and thereby permitting the stem to continue its movement in the same direction without interference until the clamping squeegee firmly presses and bears against the adjacent brace of 50 an upper or lower sash, as the case may be, although, during the portion of a revolution that the curved surface of the stem abuts the shoulder, the clutch is maintained depressed, and is not restored to the normal position, namely, retracted, until the portion of the curved surface 55 of the stem adjacent the margin 31 clears or is free of shoulder 25.

Where for example, it is desired to release a frame member after having been locked against 60 the frame casing to prevent movement or rattling, clutch 21 is manually depressed by the operator to the position illustrated in Fig. 4 and against the action of the spring thereby freeing the stem from the automatic action of the 65 clutch and in this relation the stem may be turned counter clockwise, looking in the direction from eye 29' towards the squeegee that is in this relation, the squeegee of the stem and the latter moves rearwardly and away from the 70 adjacent brace of the frame previously fastened, thus permitting the slideable frame members to be adjusted in any position within their casing or, if the socket 29 is removably associated with the stem, the former may be detached from the 75 stem and the latter removed from the support

13, it being further noted, however, that with the clutch depressed, the stem may also be moved towards a brace for tightening thereagainst without interference by the clutch.

Without further description it is thought that 80 the features and advantages of the invention will be readily apparent to those skilled in the art and it is of course understood that changes in the form, proportion, and minor details of construction may be resorted to without departing from the spirit of the invention and scope of the appended claims.

I claim:

1. A fastener adapted for use on a window comprising, a supporting member having intersecting openings, a clamping element adjustably disposed in one of the openings and normally overhanging opposed sides of said supporting member, a clutch disposed in another of said openings and comprising a terminal flanged portion, a shoulder, an intermediate attenuated part and a finger piece; resilient means forming a seat for said flanged portion for normally urging said finger piece beyond said supporting member, said element including a flat face having a marginal portion being adapted on its rotation in one direction to abut said shoulder and shift the clutch inwardly as to permit the continuance of said rotation in the same direction, said face having another marginal portion cooperating with said 100 flanged portion to resist effective rotation of said element in another direction, the attenuated part of the clutch forming a recess with said shoulder and finger piece for receiving a circular part of the clamping element subsequent to the depression of said clutch.

2. A fastener adapted for use on a window comprising, a supporting member having a pair of intersecting openings, an elongated clamping element comprising a curved threaded part adjustably connected in one opening of said pair and a longitudinally disposed rectilinear face interconnecting opposed curved parts of said element, a clutch disposed in the other opening of said pair and comprising a terminal flanged portion, a shoulder, an intermediate attenuated part and a finger piece; a spring within the last mentioned opening on which said flanged portion is seated, the spring normally urging the finger piece beyond the supporting member and shifting the major part of said attenuated portion to one side of the clamping element, said flat face on the rotation of the element in one direction being adapted to abut said shoulder and drive said clutch inwardly and against the action of said 115 spring and arrange the attenuated portion in line with said element and free thereof to permit rotation of the element in one direction, said flat face in the normal position of said finger piece cooperating with said flanged portion to resist 120 effective rotation of the element in another direction.

3. A fastener adapted for use on a window comprising, a supporting member having intersecting openings, an adjustable element disposed in 140 one of said openings and having a terminal manipulator and clamping portion extending laterally of said member, a clutch disposed in another of said openings and including a flanged portion and an intermediately arranged shoulder, resilient means comprising a seat for said clutch and normally urging a manipulating part of said clutch above said member, the element having a unitary longitudinally disposed flat face adapted to abut said shoulder and depress the clutch 145 150

against the action of the resilient means on each revolution in the same direction of said element to free the latter, said face having a marginal portion thereof coacting with said flanged portion to guard said element against effective reverse displacement upon the rotation thereof in a counter direction, said clutch having an attenu-
ated part interconnecting said shoulder and manipulating part and forming a recess therewith in which a curved portion of said element is receivable to maintain the clutch in a depressed position.
